UNITED STATES PATENT OFFICE.

ANDREW GRAYDON, OF LOS ANGELES, CALIFORNIA, ASSIGNOR OF ONE-FIFTH TO J. R. RENAKER, OF LOS ANGELES, CALIFORNIA.

GARMENT SUPPORTER.

1,411,014.

Specification of Letters Patent. Patented Mar. 28, 1922.

Application filed December 15, 1919. Serial No. 345,155.

To all whom it may concern:

Be it known that I, ANDREW GRAYDON, a citizen of the United States, residing at Los Angeles, in the county of Los Angeles and State of California, have invented a new and useful Garment Supporter, of which the following is a specification.

This invention relates to supporters for maintaining garments, hose and other wearing apparel in proper adjusted position relative to the person wearing them; and also to an improved way of supporting articles of wearing apparel either in process of drying or when idle or not in use; and the invention may be said to consist in the provision of the novel features and in the improved construction, combination, and arrangement of parts as will appear later.

The principal object of the invention is to provide a garment supporter that will be especially effective in retaining its gripping contact with garments without marring, tearing or otherwise injuring the material.

Another object of invention is to provide a garment supporter that is neat in appearance and which also can be worn without discomfort to the wearer, in other words this supporter is exceedingly flat and occupies a position with the broad flat side to the wearer so that there are no uncomfortable cutting edges to contact with the person nor sharp protruding points to catch and tear wearing apparel.

Another object of invention is to provide a garment supporter that is simple and easy to construct, is strong and durable and which can be sold very cheaply; and also to provide a supporter that is easily attached to skirt bands, garters or suspenders.

Another object of invention is to provide a garment supporter that can be attached or detached to wearing apparel without visual aid; that is the supporter can be effectively operated by the sense of touch. This feature is of great importance for, as is well known, garment supporters are usually placed where it is inconvenient and oftentimes impossible to visualize them when attaching or detaching them to or from wearing apparel.

Another object of invention is to provide a garment supporter that can be attached to an ordinary clothes hanger frame or spreader so that garments when not in use

can be easily and quickly attached thereto in a neat orderly manner; also an object of this invention is to provide a garment support that can be attached to an ordinary clothes line and used in place of clothes pins.

Other objects, advantages and features of invention may appear from the accompanying drawings, the subjoined detailed description and the appended claim.

The accompanying drawings illustrate the invention.

Figure 1 is a side elevation of the garment supporter attached to a garter and supporting a stocking.

Fig. 2 is a perspective view of a pair of ordinary suspenders attached to a fragmentary portion of a pair of trousers with parts shown by dotted lines showing three garment supporters attached to the suspenders, and supporting an under-garment shown also by dotted line.

Fig. 3 is an enlarged side elevation of the garment supporter as shown in Fig. 1, with portions of the garter and stocking broken away.

Fig. 4 is an edge elevation of what is shown in Fig. 3.

Fig. 5 is an edge elevation of the garment supporter with the clasping members open.

Fig. 6 is an enlarged section on line α^6 of Fig. 3.

Fig. 7 is an enlarged section on line α^7 of Fig. 3.

Fig. 8 is a side elevation of garment hanger showing a modified form for holding the clamping members together.

Fig. 9 is a section on line α^9 of Fig. 8.

Fig. 10 is a side elevation of the spring metal plate before it is bent into form.

Fig. 11 is an edge elevation of what is shown in Fig. 10.

Fig. 12 is a front elevation of a coat hanger with three garment supporters attached to a wire extended from end to end of the coat hanger and showing by dotted lines the bottom of a pair of trousers attached to the garment supporters.

The body portion of the garment supporter 1 is stamped out of spring sheet metal in a strip having at right-angles to the ends thereof elongated extensions 2, 3 that form the gripping members of the supporter. In the elongated end 2 are stamped

rotundus protrusions 4 that are adapted to register with the holes 5 in the elongated end 3 when the spring strip is in its final bent form. The protrusions 4 and holes 5 are impressed into the strip when it is stamped from the sheet metal.

After the strip is stamped from the metal sheets it has its center portion permanently bent around an axis to form thereby the 10 equal radial arms 6, 7 and the hollow hub portion 8 which is adapted to fit loosely on one end of the link 9. Around the arm 6, 7 is slidably mounted a band 10 that is adapted to move the clamping members 2, 3 toward 15 one another when the band 10 is moved from its position in Fig. 5 to the positions shown in Fig. 1 to 4 inclusive.

The spring tension of the arms 6, 7 is sufficient to normally hold them in the position 20 shown in Fig. 5; that is they automatically separate when the band 10 is manually moved from the position shown in Fig. 4 to that of Fig. 5, and the reverse movement of the arms is accomplished by the inward pressure of band 10 when it is moved toward the 25 free end of the arms.

The other end of the link 9 can be attached to a garter 11 as shown in Figs. 1, 3, 4, 6, 7 to support a stocking 12. When so used the 30 garter is attached to the leg in the usual way and the supporter open as shown in Fig. 5. Then a portion of the top of the stocking is 35 inserted between the clamping member 2, 3 and the band 10 slipped downward to lock these parts together. When thus clasped the protrusions 4 force portions of the stockings through the openings 5 and firmly lock and hold them in place. The protrusions 4 have a flat top portion and do not, with this 40 clasping of parts, mar, tear or injure the material.

When the garment supporter is to be used with ordinary suspenders 13 the links 9 are connected thereto by the short strips 14, see 45 Fig. 2. The double dotted lines below the suspenders 13 indicate fragmentally outer and inner garments the former being attached in the usual way to the suspenders and the latter connected to the garment supporters 1 in the same way as attached to the 50 stocking heretofore described.

In Figs. 8 to 11 inclusive a modified form for locking the clapping members together is shown. As seen therein the arms 6, 7 are 55 provided with slots 15 in which is slidably secured a rivet 16 the flanges of which hold the arms 6, 7 together when in the positions shown in Figs. 8, 9; but which permit the arms to separate when moved to the dotted 60 positions shown in Fig. 9.

As seen in Fig. 12 three of the garment supporters are attached to a wire 17 ex-

tended from end to end of an ordinary coat hanger 18; and as indicated by dotted lines a garment 19 is attached to these supporters. 65

As seen in the above figure the garment supporters are substantially like those heretofore described except that the wire 17 is substituted for the link 9; and, as is clearly apparent, as many supporters 1 as desired 70 can be attached to wire 17.

Assuming that the points 20, 21 are on posts a great distance apart and are joined by the wire 17, it can easily be seen that any 75 desired number of supporters 1 can be attached to the wire; and, owing to their loose mounting thereof, they can be moved along the line to various desired positions so that these supporters can be substituted for ordinary clothes pins. 80

In operation the garment supporters 1 are attached as heretofore described to garters, suspenders, coat hangers or taut wires; and the bands 10 of each hanger positioned to open the clamping members 2, 3, then the garments to be suspended are attached to the supporters by slipping the bands 10 toward the clamping members thereby locking them securely in place and the material is forced through the holes 5 by the protrusions 4 so that the garments can not escape from the 90 clamps.

From the foregoing it is seen that several advantages are gained, viz. the elongated extensions 2, 3 besides giving a wider range 95 of retaining surface, also give a greater amount of comfort to the wearer when using the clasp on stockings or the like, and the protrusions 4 being flat topped eliminates all possibility of forcing them through the 100 finest fabric during clasping of the arms.

I claim:

In a garment support a spring metal plate bent around an axis and extended to form equal radial arms that are normally held 105 apart by spring tension; said arms having elongated extensions on the outer ends thereof that are integral with and at right angles to said arms; one of said elongated extensions having protrusions thereon and integral therewith that are adapted to register with holes in the other of said elongated extensions, said protrusions having a flat top; a band slidably mounted on said arms for holding said protrusions in said holes; said 110 arms being joined at their bases in the form of a hollow hub; and a link loosely mounted in said hub.

In testimony whereof, I have hereunto set my hand at Los Angeles, California, this 9th 120 day of December, 1919.

ANDREW GRAYDON.
